(57) **CLAIM**

The ornamental design for a helmet mount spacer as shown and described.

DESCRIPTION

FIG. 1 is a top, side elevational view of the spacer;
FIG. 2 is a perspective of a first side of the spacer;
FIG. 3 is a perspective of a second side of the spacer;
FIG. 4 is a perspective of a third side of the spacer;
FIG. 5 is a perspective of a fourth side of the spacer;
FIG. 6 is a side elevational view of the side illustrated in FIG. 3;

FIG. 7 is a side elevational view of the side illustrated FIG. 2;

FIG. 8 is a top, side elevational view of the spacer with a conventional night vision goggle helmet mount illustrated in phantom; and,

FIG. 9 is a side elevational view of the spacer with the conventional night vision goggle helmet mount illustrated in phantom.

In the drawings, the broken, dashed lines illustrate structures that form no part of the claimed invention. The dotted lines illustrate environment that also form no part of the claimed invention.

1 Claim, 6 Drawing Sheets
